INVENTOR.

Will J. Agnew,

BY

Geo. P. Kimmel

ATTORNEY.

UNITED STATES PATENT OFFICE

WILL J. AGNEW, OF WALKER, IOWA

BATTERY TERMINAL CONNECTER

Application filed September 30, 1929. Serial No. 396,263.

This invention relates to a battery terminal connecter and has for its object to provide, in a manner as hereinafter set forth, a device of the class referred to for insuring a firm contact with respect to the battery terminal and for reducing to a minimum the possibility of the connecter becoming loose with respect to the terminal and further to set up a battery terminal connection which can be more readily or easily manufactured than the present type of battery terminal connection now generally used.

Further objects of the invention are to provide, in a manner as hereinafter set forth, a battery terminal connecter which is simple in its construction and arrangement, strong, durable, compact, thoroughly efficient in its use, readily installed with respect to the terminal, establishing a firm contact with the terminal, quickly assembled and comparatively inexpensive to manufacture.

With the foregoing and other objects in view the invention consists of the novel construction, combination and arrangement of parts as hereinafter more specifically described, and illustrated in the accompanying drawings wherein is shown an embodiment of the invention, but it is to be understood that changes, variations and modifications can be resorted to which fall within the scope of the claims hereunto appended.

In the drawings wherein like reference characters denote corresponding parts throughout the several views:—

Figure 1 is a fragmentary view in top plan of a battery showing the adaptation with the terminal thereof of a connecter in accordance with this invention.

Figure 2 is a perspective view of the connecter disassembled.

Figure 3 is a fragmentary view in side elevation of a battery showing the adaptation with the terminal thereof of a modified form of connecter in accordance with this invention.

Figure 4 is a view similar to Figure 3 taken at right angles thereto and illustrating the modified form of connecter shown in Figure 3.

Figure 5 is a fragmentary view in top plan of a battery showing the adaptation with the

terminal thereof of still another modified form of connecter in accordance with this invention.

Figure 6 is a perspective view of one of the elements of the form of connecter shown in Figure 5.

Referring to Figure 1, 7 indicates a battery and 8 a terminal thereof. The upper portion of the terminal 8 is reduced diametrically to provide a vertically disposed extension 9 having plane sides each extending throughout in a like plane and with the planes of the sides of the extension 9 disposed in parallelism. The providing of the terminal 8 with the extension 9 forms the terminal with a pair of oppositely extending shoulders 10, 11. The body portion of the terminal 8 is of circular cross section. The top edge of the extension 9 is rounded. The extension 9 is flat and of uniform width in cross section.

Referring to Figure 3 of the drawings 12 indicates a battery and 13 a terminal thereof and the latter is provided with a tapered upper portion 14. The taper on each side of the terminal 13 is slightly curved as indicated at 15, Figure 4. The top of the tapered extension 14 is rounded.

Referring to Figure 5 of the drawings 16 indicates a battery and 17 one of the terminals thereof, and the latter is of circular cross section.

In Figures 1, 3 and 5 of the drawings a cable or conductor is indicated at 18.

The connecter shown in Figure 2 is adapted to be used in connection with the form of terminal 8. The connecter shown in Figures 3 and 4 is for employment in connection with the form of extension 14 and the connecter shown in Figure 5 is employed for use in connection with the form of terminal 17.

Referring to Figure 1 of the drawings the connecter comprises a coupling member having a substantially oval-shaped outer portion 19 which is socketed for fixedly receiving the terminal of the cable or conductor 18. The socket in said portion 19 opens at one end thereof. The outer portion 19 is in electrical contact with the cable 18. Formed integral with the portion 19 and extending inwardly therefrom and at right angles thereto is a

yoke-shaped part 20 provided with a base 21 of less length than the length of the outer portion 19. The base 21 is formed integral with the inner side of portion 19. The yoke-shaped part further includes a pair of spaced parallel arms 22, 23 having the faces thereof plane. The inner faces of the arms 22, 23 are arranged in opposed, uniform spaced relation and are flat throughout and further 10 are adapted to abut against the flat sides of the extension 9. The free ends of the arms 22, 23 are provided with aligning openings 24, 25 respectively, and which register with an opening formed in the extension 9. Each arm 15 gradually increasing in width from its inner to its outer end. The end edges of the arm are rounded.

Extending through the registering openings is a clamping bolt 26 provided with a 20 head 27 and threadedly engaging with the bolt 26 is a clamping nut 28. The nut 28 in connection with the head 27 securely binds or clamps the arms 22, 23 against the side faces of the extension 9 whereby a direct contact is had and further elements 26 and 28 function to prevent the loosening of the part 20 with respect to the extension 9. The part 20 is formed of conducting material. The 25 length of the arms 22, 23 is greater than the width of the extension 9, whereby when the conductor 18 is electrically coupled with the terminal 8 the outer portion 19 to which the conductor 8 is secured will be positioned in proximity to a side of battery 7.

35 The form of connector shown in Figures 3 and 4 is the same as that shown in Figures 1 and 2, with the exception that the inner faces of the arms 29, 30 through which extend the clamping bolts 31 have their inner faces 40 form in contour to the shape of the sides of the extension 14 so that said arms will tightly bear against the sides of the extension and in this connection see Figure 3. Otherwise than that as stated the form of connector 45 shown in Figures 3 and 4 is the same as that shown in Figures 1 and 2.

With reference to Figure 5 there is combined with the connector an adaptor referred to generally at 32 for clamping to the 50 terminal 17. The adaptor consists of a split, circular part 33 provided with a pair of apertured ears 34. The ears 34 are adapted to extend between the arms 35, 36 of the yoke-shaped part 37, which corresponds to the 55 yoke-shaped part 20 shown in Figures 1 and 3. Formed integral with the yoke-shaped part 37 is an oval shaped outer portion 38 provided with a socket in which the terminal of the cable or conductor 18 is fixedly secured. 60 The portion 38 corresponds to the portion 19.

The apertures in the ears 34 are indicated at 39 and are adapted to register with the openings 40 formed in the arms 35, 36. Extending through the registering openings is a 65 headed clamping bolt 41 and which carries

a clamping nut 42. The arms 35, 36 in connection with the bolt 41 and nut 42 clamp the part 33 tightly around the terminal 17 and further tightly clamp the ears 34 to the yoke-shaped part 37.

70 The cable terminal can be quickly removed from the battery terminal when occasion requires by a connector in accordance with this invention. Furthermore the connector enables a firm connection to be easily maintained with new terminals, or with old terminals which have become thin by corrosion or flaking.

Shoulders or stops on the terminal 8 enable the holding of the cable terminal at any desired angle as well as prevent any rotation about the terminal or clamping bolt. The connector provides for direct contact with the battery terminal whether the adaptor 32 is employed or not.

80 It is thought the many advantages of a battery terminal connector in accordance with this invention and for the purpose set forth can be readily understood, and although the preferred embodiment of the invention is as illustrated and described, yet it is to be understood that changes in the details of construction can be had which fall within the scope of the invention as claimed.

85 What I claim is:

1. The combination with a battery terminal formed with side faces, a portion of one side face being parallel to a portion of the other side face, of a connector comprising a socket forming part adapted to receive a cable terminal, a yoke-shaped part integral with said socket forming part and straddling said terminal, and means for detachably clamping said yoke-shaped part against the parallel portions of said side faces of said terminal.

100 2. The combination with a battery terminal formed with side faces, a portion of one side face being parallel to a portion of the other side face, said side faces having tapered portions arranged below said parallel portions of said faces, of a connector comprising a socket forming part adapted to receive a cable terminal, a yoke-shaped part integral with said socket forming part, and means for detachably clamping said yoke-shaped part to the side faces of said terminal.

110 3. The combination with a battery terminal having an opening, of a member having a socket disposed lengthwise and opening at one end thereof, said member disposed in a plane at right angles to the plane of said terminal, spaced, parallel, apertured parts connected with one side of and disposed at right angles to said member, said parts opposing opposite sides of said terminal, the apertures in said parts aligning with each other and with said opening, and means extending through said aligning apertures and

opening for securing said parts directly against opposite sides of said terminal.

4. In a terminal connector, a part provided lengthwise thereof with a socket for receiving an end terminal of a conductor, said socket having its mouth at one end of said part, a yoke shaped member having its base integral with one side of and disposed at right angles to said part, said base being of less length than said part, said member having its arms disposed in uniform spaced relation and with the inner side faces of such arms arranged in parallelism, each of the arms of said member in proximity to its free end formed with an opening for the passage of hold fast means for attaching the connector with a battery terminal, each of said arms gradually increasing in width from its inner to its free end.

20 5. In a combination, a battery terminal provided with an extension having portions of the sides thereof disposed in parallelism said extension formed with an opening, a socket forming part for receiving the terminal of an electrical conductor, a yoke shaped member disposed at right angles to said part and having its base integral with one side of said part, the arms of said member extending in parallel planes spaced from each other, projecting inwardly from and integral at their inner ends with said base, each of said arms in proximity to its free ends provided with an opening, the openings in said arms aligning with the opening in said extension, and means for securing said arms against the parallel disposed portions of said extension, said means extending through said registering openings.

6. In a terminal connector, a unit including a body having a socket at one end for the reception of the terminal portion of a conductor and spaced, opposed portions disposed at right angles to said socket, each of said portions provided with an opening, said openings being arranged in parallelism at points removed from said socket, and hold-fast means for connecting said unit to a battery terminal, said means including a bolt common to and extending through said openings.

In testimony whereof, I affix my signature hereto.

WILL J. AGNEW.
